UNITED STATES PATENT OFFICE.

PATRICK B. DELANY, OF SOUTH ORANGE, NEW JERSEY.

KEYBOARD TELEGRAPHIC TRANSMITTER.

No. 911,384.

Specification of Letters Patent.

Patented Feb. 2, 1909.

Application filed May 26, 1905. Serial No. 262,410.

To all whom it may concern:

Be it known that I, PATRICK B. DELANY, a citizen of the United States, residing at South Orange, in the county of Essex and State of 5 New Jersey, have invented certain new and useful Improvements in Keyboard Telegraphic Transmitters, of which the following is a specification.

This invention relates to keyboard transmitters of the general character disclosed 10 in my application for Letters Patent, No. 164,999, filed July 10, 1903.

The primary object of the invention is to avoid the use of gearing or rack-and-gear driving connections by which the contact maker is caused to travel over its table or series of contacts when its key is operated, there being certain objections, unnecessary to state here, incident to the use of such geared driving actuating devices. To this end, I provide 20 a friction drive accomplished by means of two revolving wheels, rollers or disks whose axes are out of line and between which is disposed the traveling bar carrying the 25 contact maker. Engagement of the bar with the cylinder or wheel is obtained by tilting the bar so that it is cramped between the surfaces of the cylinders, bearing against the under face of one and the top face of the other, 30 this condition being maintained during the traverse of the bar by an appropriate spring, or springs, or otherwise.

The invention includes other features hereinafter set forth.

35 It has been deemed unnecessary to show more than a single contact maker, its traveling bar and corresponding key, as all others would be duplicates thereof; and the construction and mode of operation of such apparatus is well understood.

In the accompanying drawings: Figure 1, is a somewhat diagrammatic view illustrating the construction of the key board transmitter: Fig. 2, shows a modification of the 45 electrical apparatus connected therewith: Fig. 3, shows transmission to a distance and reception by a polarized relay: Fig. 4, is a detail elevation showing the friction driven cylinders and two traveling contact bars in section. Fig. 5, a detail view showing a section of perforated transmitting tape that may be prepared by suitable punches controlled by the key board transmitter.

50 *a, b*, show two horizontally disposed cylinders, to be appropriately mounted in suitable bearings, arranged one above the other with

their axes in different vertical planes. As shown, they may be geared together and one of them provided with a pinion *b* driven in any suitable way, as by a worm *b*² on the 60 shaft of an electric motor *b*³.

c is a series or table of electric contacts hereinafter described more in detail; *d* a contact maker that traverses them; and *f* the traveling bar carrying the contact 65 maker, and which is normally drawn to its rearmost inactive position by a spiral spring *f*'. This bar is guided in posts *g*, *g*' and in a loop or eye *h* carried by the key lever *i*. It passes between the friction 70 driving cylinders whose peripheries are in different planes, there being sufficient space between the planes in which the lower surface of the cylinder *a* and the upper surface of the cylinder *b* revolve for the accommoda- 75 tion, without contact with either cylinder, of the bar *f* which normally by reason of its support in the post *g* and part *h* of the key, is held out of contact with either cylinder. If, now, the front end of the bar should be 80 depressed, it would be tilted or cramped between the two cylinders making contact with the lower surface of one and the upper surface of the other and be frictionally driven forward or in the direction of the 85 arrow.

j is the upper limiting stop of the key and *k* a spring that normally holds it against such stop, the key being shown as pivoted in the upper end of post *g*'. 90

Since there is sufficient play of the bar *f* in the part *h* to permit free traverse of the bar, a spring *m* is attached to the under side of the key in front of its pivot and bears when the key is depressed, upon the front end of the bar *f* thereby tilting it in contact with or cramping it between the surfaces of the driving rolls. When the key is depressed it is held down by a spring latch *n*, the latch or movable member *o* of which may be 95 common to all the keys and which being struck by the front end of the bar *f* when it has completed its traverse, releases the key and permits it to return to normal position. When the key so returns, the tension of 100 spring *f*' is such that the speed of the return traverse of the contact maker *d* over the table of contacts is such that instruments connected in circuit will not be affected. To insure proper contact of the bar with the 105 surfaces of the driving cylinders, I provide a second spring *m*; in advance of that *m*, 110

which is engaged by the front end of the traveling bar when the latter has completed part of its forward excursion. The traveling bars f may be of any appropriate cross section, being shown as of triangular cross section in Fig. 4 and, correspondingly, in such case, the roll b is preferably provided with triangular grooves f^2 into which the bars seat. The surfaces of the cylinders 5 may, however, be of any appropriate formation in order to accomplish the intended 10 operation.

To prevent the depression of one key lever until a previously depressed one has 15 been restored to normal position, I place on the front end of each key lever, separate, parallel projections p, p' ; and, in front of the series of key levers on a rock shaft q is mounted an angular plate having a long 20 horizontal portion q' that extends under the lower projections p' on the keys and a shorter upper horizontal projection q^2 that extends toward, but does not contact, with the upper projections p on the keys. One 25 or more springs r applied to the under surface of q' holds the latter up in normal position in engagement with the under surfaces of the projections p' of the various keys. When any key is depressed, the plate q' is 30 rocked downward thereby carrying plate q^2 under the projections p of all the undepressed keys to lock them against depression.

This apparatus has been practically constructed and experience has shown it to be 35 highly efficient. The principles involved may, no doubt, be embodied in various other forms by those skilled in the art without departing materially from this invention.

As shown in Fig. 1, one pole of a battery or 40 generator MB is connected with the frame of the instrument and consequently with the various trailers d , and the other pole is connected with the contacts in the several tables or series of contacts such as e . In this 45 instance, as well as in Figs. 2 and 3, the contacts are arranged for the transmission of the letter "J" of the Morse code. The active or battery connected contacts required for the formation of the letter J are numbered from 1 to 8 inclusive and are of uniform size but of dissimilar spacing to produce dots and dashes. In Fig. 1, contacts numbered 1, 3, 5 and 7 are connected with the battery MB through a punch magnet M, 50 while numbers 2, 4, 6 and 8 are connected through punch magnet M' . The normally retracted armature levers of these magnets when attracted deliver a blow upon the punches m, m' to perforate a continuous tape 55 traversing through the punch block N. A section of ribbon or tape punched for the letter "J" is shown in Fig. 5 and may be used for transmission in machine telegraphy having a chemical recorder. Such an arrangement of perforations and the method of sig-

naling therewith are shown in patents heretofore granted to me, viz: No. 720,004, dated Feb. 10, 1903 and No. 790,193, dated May 16, 1905. When the key i is depressed and the traveling bar f is brought into driving engagement with the cylinders a, b , the trailer is moved forward at such speed that contact with the several live contact pieces 1 to 8 is of such duration as to be effective in operating the magnets M, M' . When the trailer is 70 upon contact 1, punch magnet M is operated and perforation 1' is formed in the tape (Fig. 5). During the long interval representing a dash in which the trailer is passing to contact No. 2, the tape is traveling at uniform speed through the punch block and when the trailer comes upon No. 2 punch magnet M' is operated and perforation 2' is formed in the tape. When the trailer is upon No. 3, magnet M is again operated to form the perforation 3' and during the shorter interval 80 between 3 and 4 which is required for formation of a dot signal, the tape is traveling, and when d comes upon contact 4, punch magnet m' is actuated and perforation 4' formed in the tape, and so on, the characters formed being dash, dot, dash, dot. In the system of automatic machine telegraphy referred to, the dash signal is initiated by perforation 1' in one row and terminated by 2' in the other 90 row, the interval between the two being of such length as to result in the production at the receiver of a dash. The interval between 3' and 4' being very much less, a dot is produced at the receiver. In Fig. 3, the 100 same arrangement of contacts is shown. The generator MB' is grounded in the middle. One pole is connected to the contacts 1, 3, 5 and 7 and the other pole to contacts 2, 4, 6 and 8. The trailer d is connected to line 105 which may be of any feasible length, and the transmitted signals are received upon a polarized relay receiver as dots and dashes manifested by any suitable instrument locally controlled by the relay.

In Fig. 2, the punch magnets M, M' are connected, as before, to a generator MB, but the branch circuits therefrom, including the punch magnets, are controlled at the front stops of relays G, G' connected in circuit with a local battery l, b that is connected with the contacts 1 to 3 inclusive.

In the arrangement shown in Figs. 1 and 3, the tape punching may be entirely local and for the purpose merely of preparing the tape for automatic or machine transmission of the message; or, the punching devices may be located at an indefinite distance from the key board transmitter and in that event, the punch magnets or other devices for recording the message upon the tape may constitute receivers of the transmitted message that may be read from the perforations in the tape, and by means of it, relayed or retransmitted into another circuit.

The spring *d* is so constructed and arranged that proper contact is made between it and the series of contacts when the rear end of the bar is thrown upward by depression of the key. There is, therefore, no necessity for inverting the series of contacts and spring trailer so that the latter will traverse in contact with their under faces.

I claim as my invention:

- 10 1. In a key-board transmitter, the combination of a series of message transmitting contacts, a contact member adapted to traverse them, an endwise traveling bar carrying the contact maker, friction driving wheels or cylinders arranged with their axes in different lines transverse to the bar, and between the adjacent surfaces of which the bar normally lies, a finger-piece or key-lever operatively connected with the bar to tilt it when
- 15 20 the finger piece is depressed to thereby throw it into frictional engagements with the upper surface of one cylinder and the lower surface of the other whereby the bar is frictionally driven forward to carry the contact maker over the series of contacts, and means for returning the bar to normal position.

2. In a key-board transmitter, the combination of a series of message transmitting contacts, a contact member adapted to traverse them, an endwise traveling bar carrying the contact maker, friction driving wheels or cylinders arranged with their axes in different lines transverse to the bar and between the adjacent surfaces of which the bar normally lies, a finger-piece or key-lever, a loose connection between it and the bar, a spring interposed between the bar and key-lever whereby on depression of the key-lever

30 35 40 45 the front end of the bar is depressed so that the bar is brought into contact with adjacent surfaces of the driving cylinders and is driven forward to carry the contact maker over the series of contacts and a spring for automatically returning the bar to normal position.

3. In a key-board transmitter, the combination of a series of message transmitting contacts, a contact member adapted to traverse them, an endwise traveling bar carrying the contact maker, friction driving wheels or cylinders arranged with their axes in different lines transverse to the bar and between the adjacent surfaces of which the bar normally lies, a finger-piece or key-lever operatively connected with the bar to tilt it when the finger piece is depressed to thereby throw it into frictional engagement with the upper surface of one cylinder and the lower

50 55 60 surface of the other whereby the bar is frictionally driven forward to carry the contact maker over the series of contacts, means for locking the key in depressed position, means for automatically releasing the key when the

bar has completed its forward traverse and means for returning the bar to normal position.

4. In a key-board transmitter, the combination of a series of message transmitting contacts, a contact member adapted to traverse them, an endwise traveling bar carrying the contact maker, friction driving wheels or cylinders arranged with their axes in different lines transverse to the bar and between the adjacent surfaces of which the bar normally lies, a finger-piece or key-lever operatively connected with the bar to tilt it when the finger piece is depressed to thereby throw it into frictional engagements with the upper surface of one cylinder and the lower surface of the other, whereby the bar is frictionally driven forward to carry the contact maker over the series of contacts, means for locking the key in depressed position, means for automatically releasing the key when the bar has completed its forward traverse, means for returning the bar to normal position and means adapted to lock the other key levers of the instrument against depression until a depressed key has been released.

5. In a key-board transmitter, the combination of a key-lever having projections *p*, *p'*, and a rocking locking device comprising the parts *q*, *q'*, coöperating for the purpose set forth.

6. A key-board transmitter, comprising the combination with a movable contact maker, an endwise traveling bar on which it is mounted and revolving friction driving members located on opposite sides of the bar and adapted to frictionally actuate it in one direction.

7. In a key-board transmitter, the combination with a movable signal contact effecting member, of rotating friction drivers arranged on opposite sides of such member, with their axes in different transverse lines, and operating as described.

8. In a keyboard transmitter the combination with a movable contact maker thrown into operation by depression of its key, a series of contacts, two for each dot and two for each dash, over which the contact maker traverses, the contacts for dots being separated by uniform space and the contacts for dashes being separated by space corresponding to the length of the dash, each dot and dash contact being connected to a source of current of opposite polarity to the contact in front or behind it.

In testimony whereof, I have hereunto subscribed my name.

PATRICK B. DELANY.
